UNITED STATES PATENT OFFICE.

LAWRENCE P. WELFLEY, OF BRIDGEPORT, CONNECTICUT, ASSIGNOR TO
THE AUTOMATIC SCALE COMPANY, A CORPORATION OF NEW JERSEY.

DASH-POT FOR SPRING-SCALES AND THE LIKE.

No. 825,992.

Specification of Letters Patent.

Patented July 17, 1906.

Original application filed November 8, 1904, Serial No. 231,952. Divided and this application filed July 26, 1905. Serial No. 271,368.

To all whom it may concern:

Be it known that I, LAWRENCE P. WELFLEY, a citizen of the United States, residing at Bridgeport, Connecticut, have invented 5 certain new and useful Improvements in Dash-Pots for Spring-Scales and the Like, of which the following is a specification.

My invention has been designed in order to overcome the vibration of the springs in a 10 weighing-scale, and at the same time I have aimed to provide a device which will offer no resistance to the downward movement of the parts in the act of weighing and will stop the vibrations of the springs as soon as they have 15 fully distended, due to the weight of the goods placed on the pan. I do not wish, however, to limit my invention to use in connection with spring-scales.

The invention consists in the features and 20 combination and arrangement of parts hereinafter described, and particularly pointed out in the claims.

So far as the main features of the invention are concerned this application is a division of 25 that filed by me November 8, 1904, Serial No 231,952.

In the drawings, Figure 1 is a side view of the improved dash-pot. Fig. 2 is a sectional view of the same. Fig. 3 is a plan view of the 30 invention.

In order to overcome the vibration of the springs in the scale and at the same time provide a device which will offer no resistance to the downward movement of the parts in the 35 act of weighing and will stop the vibrations of the springs as soon as the springs have fully distended, due to the weight placed on the pan, I have provided a special form and arrangement of dash-pot or device associated 40 with the platform-weighing mechanism.

This device consists of a cylinder 1, having ears 2, by which it may be secured. This cylinder has within it a second cylinder 3, preferably cast therewith and having a space 45 4 between the two cylinders. These cylinders communicate with each other through an opening 5, extending through the wall at the lower end of the inner cylinder. This opening is regulated as to size by a valve 6,

50 consisting of a cylindrical rod extending vertically in the space between the cylinders, the lower end of the cylindrical rod being cut away at 7, so that by turning the said rod the opening 5 will be closed when the cylindrical 55 portion is opposite the said opening, or by turning the rod until the cut-away portion is

opposite the opening 5 more or less different effects may be secured, owing to the different areas of the port thus afforded between the two cylinders.

Within the inner cylinder a piston or plunger of any suitable form reciprocates. This piston may be described as being generally of globular form in that it has rounded bearing-surfaces 8, engaging with the inner periphery of the inner cylinder, the upper and lower portions of the said piston or plunger being of a smaller diameter than the middle portion. The piston or plunger is hollow and contains a ball-valve 9, adapted to a 60 seat 10, having an opening 11, through which the liquid contained in the cylinders is free to pass when the ball-valve is off its seat, as will be hereinafter described. The piston or plunger is further provided with ports 12, 65 connecting its interior with the interior of the inner cylinder. The piston is rigidly connected with a rod 13, which in turn is suitably connected with the scale. The arrangement is such that in the vertical movement of the piston it may have slight rocking movement, due to its globular shape, against the interior walls of the inner cylinder.

Supposing the cylinders to contain the 75 appropriate amount of liquid, the action is as follows: When the piston is depressed under the action of the weight of the material placed upon the platform or scale pan, and the springs are distended by the said 80 weight, the oil or other fluid contained in the inner cylinder is forced through the piston or plunger, for which purpose the ball-valve rises from its seat, and this oil or liquid passes out through the ports 12 into the part 85 of the inner cylinder above the piston or plunger. This allows the piston or plunger to descend with comparative freedom, which may, however, be regulated by the amount of opening of the port 5; but as soon as the 90 limit of downward movement of the parts has been reached, due to the weight of the material or article placed on the scale pan or platform, vibration of the connections will be checked by the action of the piston or 95 plunger, for upward movement of the parts will be checked or prevented by the valve seating itself at once, and thus preventing the free flow of the liquid therethrough, and consequently the piston will now have a 100 suction action, and its upward movement will be retarded corresponding to the degree of 105

opening of the port 5. In other words, the upward movement of the piston due to the tendency of the parts to vibrate when the springs are distended, causes the closing of 5 the ball-valve 9, which tends as the piston goes up to form a vacuum beneath the said piston, which is filled only by suction through the port 5, and as this port can be regulated as to its area the action of the piston can be 10 nicely adjusted.

As above stated, the piston-rod is rigidly connected with the piston, while the latter itself is adapted to have a certain amount of 15 rocking movement on the walls of the cylinder.

It will be noticed that the inner cylinder is open at the top and is of less height than the outer cylinder. Any liquid which gets 20 above the piston will when said piston rises discharge over the top of the inner cylinder into the outer cylinder. The valve-rod 6 extends through the top or head of the outer cylinder and has connected therewith a lever or arm 14, by which the valve-rod may be 25 turned. A segment 15, having notches, is adapted to be engaged by the said lever, whereby the valve-rod will be held in adjusted position.

I prefer to hold the head of the outer cylinder in place by means of clips 16, consisting of flat pieces of metal arranged at an inclination and bearing at their ends against the under side of the head and the inner side of the outer cylinder, screws 17, passing 30 through the head and into the said clips, serving to draw the parts into close contact. The opening in the upper cylinder-head is 35 larger than the diameter of the piston-rod.

In Fig. 2 I show a leaf or spring blade 17', 40 attached at its upper end to the inner cylinder and with its lower end normally sprung away from a port 18 at the bottom of the inner cylinder, connecting the interior of the inner cylinder with the space 4 between the 45 two cylinders.

The action is as follows: The upward movement of the piston creates a suction in the inner cylinder, which causes the spring-blade to be drawn inwardly and to close 50 over the port 18. At the end of the upward stroke of the piston the suction action ceases in its effect on the spring-blade, which now at its lower end springs away from the port 18 and opens the same. This will entirely

destroy any suction or partial vacuum 55 which may be present in the inner cylinder such as would exert an undesirable influence on the piston. With this form of dash-pot all the features before described are included in practice.

I claim—

1. Means for arresting vibration consisting of an inner cylinder, a valved piston therein, an outer cylinder communicating with the inner cylinder at its lower end through an 60 opening and also with said cylinder at its upper end, the water being free to pass from the top of the inner cylinder through the space between the cylinders and into the inner cylinder at the bottom, and means for controlling the lower opening leading to the inner cylinder consisting of a rod extending between the cylinders from the lower end thereof and out through the top of the casing, substantially as described.

2. In combination with the cylinder and piston with an opening in the cylinder for the flow of fluid therethrough, said cylinder being surrounded by an outer chamber, an automatic closure for the opening adapted to 65 close under the action of the piston suction and adapted to open as the suction-pressure ceases at the end of the piston-stroke, substantially as described.

3. In combination with the cylinder and 70 piston with an opening in the cylinder for the flow of fluid therethrough, said cylinder being surrounded by an outer chamber, an automatic closure for the opening adapted to close under the action of the piston-suction 75 and adapted to open as the suction pressure ceases at the end of the piston-stroke, said closure consisting of a leaf-spring having its free end closing the opening, substantially as described.

4. In combination with the cylinder and piston, a spring-valve arranged to be closed by the suction within the cylinder created by the piston, said valve opening automatically as the piston ceases its movement, substantially as described.

In testimony whereof I affix my signature in presence of two witnesses.

LAWRENCE P. WELFLEY.
